FLOWER POT BRACKET FOR MONUMENTS

Francis P. Hare, 322 Felsway W., Medford, Mass.

Filed Aug. 3, 1964, Ser. No. 81,147

Term of patent 14 years

(Cl. D35—3)

FIG. 1 is a perspective view of a flower pot bracket for monuments showing my new design;

FIG. 2 is a side elevation thereof; the broken lines being shown for illustrative purposes only; and

FIG. 3 is an end view thereof.

I claim:

The ornamental design for a flower pot bracket for monuments, as shown and described.
